[57] CLAIM

The ornamental design for a quick release clip, as shown and described.

DESCRIPTION

FIG. 1 is an exploded, perspective view of a two-piece quick release clip having an insertable piece and a receiving piece, made in accordance with the principles of the present invention;

FIG. 2 is a left side view of the insertable piece thereof; FIG. 3 is a right side view of the receiving piece thereof; FIG. 4 is a left side view of the receiving piece thereof; FIG. 5 is a right side view of the insertable piece thereof; FIG. 6 is a top plan view of the insertable piece thereof; FIG. 7 is a top plan view of the receiving piece thereof; FIG. 8 is a bottom plan view of the insertable piece thereof; FIG. 9 is a bottom plan view of the receiving piece thereof; FIG. 10 is a rear end view of a proximal end of the receiving piece thereof;

FIG. 11 is a front end view of a distal end of the receiving piece thereof;

FIG. 12 is a rear end view of the proximal end of the insertable piece thereof; and,

FIG. 13 is a rear end view of the distal end of the insertable piece thereof.
